UNITED STATES PATENT OFFICE.

OTTO KLATTE, OF NEUWIED, GERMANY.

ROLLING-MILL FOR MANUFACTURE OR SHAPING OF CHAINS.

SPECIFICATION forming part of Letters Patent No. 537,781, dated April 16, 1895.

Application filed April 12, 1894. Serial No. 507,267. (No model.) Patented in Luxembourg August 10, 1893, No. 1,874; in France August 11, 1893, No. 232,132; in England August 12, 1893, No. 15,403; in Norway August 16, 1893, No. 3,391; in Belgium August 18, 1893, No. 106,021, and in Italy September 30, 1893, LXVIII, 88.

To all whom it may concern:

Be it known that I, OTTO KLATTE, a subject of the King of Prussia, residing at Neuwied-on-the-Rhine, Germany, have invented certain new and useful Improvements in Rolling-Mills for the Manufacture or Shaping of Chains, of which the following is a specification.

My invention has reference to those rolling mills which have four rolls arranged in two pairs at right angles to each other, the peripheries of which have grooves for the manufacture of smooth bars or are provided with cavities and protuberances in such a manner, that on smooth bars corresponding impressions will be produced and for instance an X shaped bar will be transformed into the shape of a series of connected chain links, or the roughly formed links of a chain will be compressed into the desired finished shape.

Foreign patents have been granted for this invention as follows: in France, No. 232,132, dated August 11, 1893; in Belgium, No. 106,021, dated August 18, 1893; in Italy, No. LXVIII, 88, dated September 30, 1893; in Norway, No. 3,391, dated August 16, 1893; in Luxembourg, No. 1,874, dated August 10, 1893, and in Great Britain, No. 15,403, dated August 12, 1893.

The subject of the present invention relates to arrangements for adjusting the rolls in such machines in the horizontal and vertical planes and for preventing the jumping of the rolls. A mill provided with such arrangements is represented in the accompanying drawings, in which—

Figure 1 is a front view partly in section; Fig. 2, a plan of the mill, and the left half of Fig. 3 is a section on the line 19—20, Fig. 1, looking from left to right, while the right hand half of Fig. 3 represents a section on the line 21—22 of Fig. 1 likewise looking from left to right.

The shaft 21 of each of the four rolls is supported in a bearing at each end in order to prevent the bending or deflection of the same.

The two bearings of the vertical shaft of each horizontal roll form a continuous yoke piece 22. Each of these double bearings is transversely movable on horizontal guides 47 which are attached to standards 23. This movement is effected by adjusting the lateral

wedges 24, Fig. 3, (right hand,) which bear on one side against the bearings 22 and on the other side against shoulders 48 of the standards 23. To each of these wedges a bolt 49 is attached, which passes upward and through a lug 50 on the standard 23 and is provided both above and below this lug with a nut. The guides 47 of each forked bearing are attached to a plate 51, Fig. 1 (right hand) and this plate has two vertical guides 52 on the opposite side, Figs. 1 and 2 (left hand), which are movable in vertical grooves in the standard 23. This plate 51 rests at the bottom on two wedges 25, Figs. 1 and 3, of which only one can be seen in the drawings. The one wedge is situated under the one and the other wedge under the other end of the plate 51, and each wedge rests on a lug 53 of the standard 23. The wedge, which is not drawn, has a bolt 54 which passes through a hole in the wedge shown and on the farther side of the same carries a collar 55 and a nut 56. When this nut is tightened the two wedges 25 approach one another and thereby raise the plate 51 and with it the forked bearing 22 and the shaft carried in the same. For facilitating the vertical adjustment each forked bearing 22 is connected to a strap 26, which hangs from the cross girder 27 connecting the two standards 23 at the top and by turning the adjusting screw 28, which passes through the strap, the forked bearing can be either raised or lowered. The strap 26 is at the bottom at 29 detachably connected to the bearing 22 in order that the latter can be sufficiently displaced to allow of the changing of the rolls. When the bearings 22 have been properly adjusted they are securely bolted to the standards 23 by the bolts 30, Fig. 1 left hand.

The two bearings of the upper roll form a part of the cross girder 27, which is adjustable in the vertical direction by means of the regulating screws 31, Fig. 1 top, which rest with their bottom ends on the standards 23. The cross girder 27 is connected to the bearings of the lower roll by means of vertical stays 32 Fig. 3 left hand, which secure the cross girder against upward pressure. These stays, which are strongly made, are placed as nearly as

possible to the vertical middle plane 19—20 Fig. 1 of the frame of the machine and to the vertical middle plane at right angles thereto, so as to reduce the deflections of the cross girder, and thereby the jumping of the upper roll, to a minimum.

A to and fro movement of the cross girder 27 is prevented by the tongues 33 on the heads of the standards 23 Figs. 1 and 2 right hand, 10 which fit in corresponding grooves 34 in the cross girder, and further by means of the lateral bolts 35 passing through the heads of the standards and vertical slots 36 in the cross girder.

15 I have already explained that the two horizontal rolls are adjustable vertically and horizontally in a plane parallel to the plane of the standards. These standards 23 are made movable on the bed plate in order that the 20 horizontal rolls may also be adjusted in a plane perpendicular to that of the standards and to permit of the substitution of smaller or larger rolls. When the standards are thus moved the stays 37 connecting them must of 25 course be correspondingly adjusted. These stays 37 as well as supporting the standards also prevent the springing of the horizontal rolls. The bearings of the lower roll are also movable on the bed plate to insure accurate 30 adjustment Fig. 3.

The driving shaft 38, which is detachably connected with the shaft of the upper roll Fig. 1 left, is adjusted by means of the screw coupling 39 and the regulating screw 40, and the 35 intermediate shaft 41, which is likewise detachably connected with the shaft of the lower roll, is adjusted by the wedge 42. The shaft 38 drives the intermediate shaft 41 and the lower roll by means of the gearing 43, 44.

40 The motion communicated directly to the upper roll by the driving shaft 38 is transmitted to the bevel wheels 46 on the horizontal rolls by the bevel wheels 45 on each side of the upper roll. Various sizes of gear and 45 bevel wheels are provided to correspond to the different diameters of the various rolls.

The method of driving the rolls described above is principally suitable for the rolling of large chains. For smaller chains or for the 50 pressing in of smaller cavities the power required is not so great and therefore it is not necessary to drive the lower roll by means of gearing. Instead of the gearing, both sides of the lower roll and the under sides of the 55 horizontal rolls are provided with bevel wheels which engage in one another similarly to the bevel wheels 45 and 46. This arrangement can also be used in combination with the intermediate shaft.

60 Having fully described my invention, what I desire to claim and secure by Letters Patent is—

1. In a rolling mill, the combination with its main frame of a set of rolls, an independent 65 frame containing both bearings of the shaft of one of said rolls and means for adjusting such independent frame vertically and later-

ally with reference to the main frame, substantially as set forth.

2. In a rolling mill, the combination with its 70 main frame, of a set of horizontal rolls, an independent frame containing both bearings of the shaft of one of said rolls, vertical guides along the main frame and wedges for producing movement of the independent frame along 75 said guides, substantially as set forth.

3. In a rolling mill, the combination with its main frame, of a set of horizontal rolls, an independent frame containing both bearings of the shaft of one of said rolls, vertical guides 80 along the main frame, wedges for producing movement of the independent frame along said guides and a screw threaded bolt engaging with one of said wedges for actuating the same, substantially as set forth. 85

4. In a rolling mill, the combination with its main frame, of a set of horizontal rolls, an independent sectional frame containing both bearings of the shaft of one of said rolls, a plate mounted on vertical guides along the 90 main frame and carrying lateral guides for the part of the independent frame containing said bearings, mechanism for varying the elevation of said plate with reference to the main frame, and means for adjusting the part of the 95 auxiliary frame containing the bearings laterally with reference to the said plate, substantially as set forth.

5. In a rolling mill, the combination with its main frame, of a set of horizontal rolls, an independent frame containing both bearings of the shaft of one of said rolls, a strap suspended from the main frame and detachably connected to said independent frame, and adjustable supporting devices, whereby said independent frame can be raised and lowered, 100 substantially as set forth. 105

6. In a rolling mill, the combination with its main frame, of a set of horizontal rolls, an independent frame containing both bearings of the shaft of one of said rolls, the upper part 110 of the main frame made adjustable in height, a strap suspended from said upper part and detachably connected to said independent frame, and adjustable supporting devices 115 whereby said independent frame can be raised and lowered, substantially as set forth.

7. In a rolling mill, the combination with its main frame, of an independent frame containing the bearings of one of the rolls, and a pair 120 of wedges for varying its position with reference to the main frame, and joint means for actuating said wedges simultaneously, substantially as set forth.

8. In a rolling mill, the combination with its main frame, of an independent frame containing the bearings of one of the rolls, a pair of 125 wedges for varying its position with reference to the main frame, and a joint screw bolt for actuating said wedges, substantially as set forth. 130

9. In a rolling mill, the combination with a set of rolls, a main frame comprising a stationary platform and standards capable of lat-

eral adjustment on the same, an independent frame containing the bearings of one of said rolls, means for adjusting the position of said independent frame with reference to said standards, and adjustable lateral connections between said standards, substantially as set forth.

In testimony whereof I have signed my name to this specification in the presence of two subscribing witnesses.

OTTO KLATTE.
